UNITED STATES PATENT OFFICE

JAMES DENARO, OF CAMBRIDGE, MASSACHUSETTS

ICE-CREAM-CONE-MAKING MACHINE

Application filed December 28, 1925. Serial No. 77,911.

This invention relates to ice cream cone making machines, and with respect to certain more specific features thereof, to so-called "hand operated" machines having a multiplicity of molds designed to produce cones, or other pastry containers of good quality at a high rate per unit of time.

The invention has for one of its objects to provide a machine which shall be low in first cost, economical in floor space, economical in fuel consumption, yet producing per hour more finished and usable containers than the so-called automatics in use at the present time.

Another object of the invention is to provide a carrier for the female molds which shall be movable into and out of registration with the burners or ovens and which permits the easy removal of the molds so that others for a different type or size of container may be readily substituted.

Another object is to have a main frame, providing for the arrangement thereon of a series of mold carriers and core heads as independently operable units positioned in a row, so that a single operator may pass from one to the next and so on until the units have been successively filled and set in baking position after which the operator may return to the first unit to effect the discharge of the baked containers and the refilling of the molds with batter from a single batter supply device which is movable with the operator to each successive unit.

Other objects will be in part obvious and in part pointed out particularly hereinafter.

The invention accordingly consists in the various features of construction, combinations of elements and arrangements of parts which will be exemplified by the construction hereinafter set forth and the scope of the application of which will be indicated by the appended claims.

Referring now more particularly to the drawings wherein is shown one of various possible embodiments of the invention;

Fig. 1 is a top plan view of my improved machine.

Fig. 2 is a top plan view of two of the units which go to make up the complete machine,

these units being enlarged over the showing in Fig. 1.

Fig. 3 is a view in side elevation of one of the units shown in Fig. 2.

Fig. 4 is a plan view of the mold carrier and assembly mold.

Fig. 5 is a sectional view taken on the line 5—5 of Fig. 4.

Fig. 6 is a plan of the batter feeding mechanism.

Fig. 7 is a view in vertical central section of Fig. 6.

Fig. 8 is a view in vertical section taken on the line 8—8 of Fig. 6.

Fig. 9 is a view in side elevation of a modified form of the devices for actuating the mold elements.

Fig. 10 is a plan view of the mechanism shown in Fig. 9.

Fig. 11 is a plan view of a modified form of batter-supplying mechanism and Fig. 12 is a view in side elevation, partly in section, of the mechanism shown in Fig. 11.

Generally the machine comprises a main frame and a plurality of burner frames arranged in a row at the main frame. Slide ways or rails are provided running to each of the burner frames, and mounted for rolling engagement with these slide ways are mold carrying sub-frames, each of which is movable independently of the other, so that each sub-frame, carrying a multiplicity of molds, may be pulled forwardly from its oven or burner frame and located over a discharge trough, enabling the operator to open the molds and empty them of the baked product.

The main frame includes slide rails running the length of the machine at right angles to the slide rails for the mold-carrying frames.

A batter supply mechanism is arranged for sliding movement on the latter rails so that after the molds have been cleared of the baked cones or cups they may be closed in position of registration with the batter supply mechanism as it is moved on its rails. A core carrier having a multiplicity of cores corresponding in number to the molds hereinbefore referred to, is movably mounted on the main frame over each burner frame. A separate movable core carrier is provided for each

60

65

70

75

80

85

90

95

100

unit of the machine. The operation of the machine is in general as follows:

Starting with the left-hand unit, the operator closes the female molds on the mold carrier and moves the batter supply mechanism into registration above the closed molds. He then operates a handle by which a multiplicity of nozzles are opened to discharge a predetermined quantity of the batter into each mold cavity. The mold carrying frame is then moved rearwardly on its slides into a position of registration with the burners below and the male cores above. By operating another lever at the forward end of the unit, the core carrier is caused to descend into the molds forming the batter up around the cores and closing the cavity provided between the side walls of the female molds and the outside walls of the cores. In giving this movement, the operator works the cores up and down slightly, allowing expansion to take place and the steam gases to escape, after which the cores are secured in baking position by a toggle effect of certain levers in the actuating mechanism.

The operator then proceeds in the same fashion with each one of the eight, or more units of the machine, the length of time taken to perform these operations on the remaining units of the machine being gauged to allow the complete baking of the batter introduced in the first unit. The operator then returns to the first unit, operates the core carrier to raise the cores out of the mold so that the sub-frame with the finished baked cones may be withdrawn from the oven and located over a discharge trough. In this preferred embodiment of the invention the female molds are arranged in separable halves so that by the use of a hand extractor having a series of properly spaced projections, the operator may split or separate the molds and push off the cones at the same time. As the cones are pushed off, they fall from the open mold halves and are directed by the discharge chute usually through the floor of the building to another department where they are stacked and packed for shipment.

Referring now more particularly to the drawing there is indicated at 20, (Fig. 3) a flooring through which passes a discharge chute 21 having an enlarged mouth 22.

The main frame is built up from the flooring by spaced uprights 23, longitudinal angle irons 24 at the rear of the machine, and longitudinal irons 25 at the front of the machine. Spaced rails 26 extending from front to rear of the machine joining respectively with the spaced uprights 23. The rails 26 serve as tracks for mold carrying sub-frames 27 which will later be described in detail. To each of the rails 26 near the rear of the machine a depending piece 28 is attached and these pieces at their lower ends are fixed to members 29 which in turn are attached to the rear

uprights 23. Upper slide bearing pieces 30 are fixed to the rails 26 and lower slide bearing pieces 31 are fixed to the members 29, the structure forming vertical slide bearings for a core head 32 which has oppositely disposed vertical slides 33 arranged in the bearings.

Lengthwise of the machine, but traversing the individual units thereof, is a pair of rails 34. These rails are supported by uprights 35 from the flooring 20, the uprights tying to the rails 26 as indicated at 36. The rails 34 extend some distance beyond the extreme left hand unit as shown in Fig. 1 of the drawings so that a batter supply mechanism 40 arranged for sliding movement on the rails may be moved to a position of rest beyond the units, enabling the operator to manipulate the molds of the first or left hand unit without the interference of the batter tray.

The fuel supply is by a gas main 41 coming through the flooring 20 and from which separate feed frames 42 run to the individual units between the rails 26. The feed frames 42 supply the fuel for heating the mold units from below. For heating the cores on the core head 32 a series of pipes 43 is fixed above the core head and connected to the main 41 by flexible conductors 44. Individual valves are provided for the core gas feed and the mold gas feed and these valves are controlled by handles or hand wheels 45 and 46 respectively, arranged at the front of the machine and at each unit.

The mold carrier 27 of each unit is in the form of a rectangular frame 50 in which are journalled wheels 51 adapted to roll on the track constituted by the spaced rails 26. The side pieces 52 of the frame 50 form a slide for a plurality of split female molds 53, the frame being sufficiently long to permit the complementary mold sections to be separated successively to allow the baked products to be extracted. Each pair of female molds is formed with mold cavities 55 so that when closed a cup or cone shaped opening is formed to receive a charge of batter and the male core. In this present embodiment of the invention there are eight baking units. Each baking unit comprises ten mold pairs and each mold pair is formed with seven cavities. The baking time allowed for each unit is from two and a half to three minutes. This allows the operator suitable time to do the unloading and refilling operations on the remaining seven units, returning to the first unit at the end of the baking period to unload and refill. The capacity of the machine is, therefore, per unit of baking time five hundred and sixty cups or approximately ten thousand per hour.

The core head 32 carries seventy male cores 60 each mounted on the head by a bolt, the shank of which passes through a hole in the head slightly larger than the shank. This allows the cores a slight lateral shaft in any direction to adjust the cores to the molds when

70

130

the head is moved downwardly into forming and baking position.

The actuating devices for the core head and the mold carrying frame are shown best in Figs. 1 and 3 of the drawings. On lugs 61, spaced on and projecting from the front cross piece of the mold carrying frame, two arms 62 are pivoted. These arms with a cross connecting rung 63 constitute a handle by which the said frame may be withdrawn from and returned to the burners. The arms 62 extend upwardly or inwardly beyond the pivot points on lugs 61, and pivotally connect at 64 with links 65 which in turn pivotally connect with lugs 66 secured to the front wall of the most forward female mold section 53. When the handle 63 is moved downwardly around its pivot on lugs 61 the forward mold section is moved forwardly separately from its complementary section. The other molds are then broken by the operator with the use of a handle 70 shown by dotted lines in Figs. 4 and 5, the handle having a cross bar 71 reinforced by diagonal struts 72. The cross bar has a plurality of depending fingers 73 of suitable shape and in number corresponding to the number of cavities in a mold section. The operator introduces the fingers to the mold cavities drawing each successive and corresponding half mold toward him, moving also the remaining half of the last opened mold and closing the gap. By a slight back and forth movement of the handle the baked cups are effectively separated from the walls of the mold cavities and they then drop to the chute 21. The completion of this operation leaves the molds as shown in the second unit of the machine in Fig. 1 of the drawings. The operator then moves the handle upwardly, which, through links 65 moves the mold sections back, closing the gap at the rear of the mold carrier and locking the sections together by a toggle effect of links 65 and lever arms 62, as clearly shown in Fig. 3.

The core heads are moved upwardly and downwardly by handles and connected links and levers as follows. In each unit the slides 33 to which the core head is connected have at their upper extremities a connecting cross bar 80. A pivoted link 80' couples the bar 80 with one end 81 of a beam 82 fulcrumed at 83 on the main frame. The other end 84 of the beam is pivotally connected at 85 to the upper end of a link 86, the lower end of which has a pivoted connection at 87 with an arm 88 journalled in a fixed bracket 89. The arm has a connection by means of a long link 90 with a lever 91 journalled in a fixed bracket 92 at the front of the machine. The upper end of lever 91 is formed as a handle 93. Movement of the handle upwardly into the position shown by the full lines in Fig. 3 forces the core head down causing the cores to enter the mold cavities and finally locks

the parts by a toggle effect of link 86 and arm 88. A counterbalance weight 94 is suspended from the end of the beam 82 to assist the operator in lifting the core head. Sheet metal cover plates 95 may be arranged over the gas feed for the core head, as shown in Fig. 1, for the purpose of confining the heat. In the modified form of core actuating means shown in Figs. 9 and 10 of the drawings, additional pressing and toggle locking means are employed for the purpose of applying pressure at a plurality of points on the core head. An extra frame 100 is built up on each rail 26, supporting a cross bar 101. Journal boxes 102 on either side of the unit center line, have pendant links 103 connected to link 104 by pivot pins 105. The links 104 connect to the cross bar 80 in the same manner as links 80' are connected. Pivotally secured to the joined ends of links 103 and 104 by the pivot pin 105 is a link 106 which connects at 107 with a forked connection 108. Opposite branches of the fork 108 connect above at 109 with extensions 110 of the uprights 23, and below at 111 with the arm 88 by pivot pin 87. By this construction the arm 88 controls the toggle links 103 and 104 as well as the toggle link 86. Movement of the handle 93 applies pressure at three points on the cross-bar of the core head and locks the latter with its cores in the molds by actuating the three toggles. Generated steam and the batter expansion under the heat of the molds exerts a great upward pressure on the core head. The modified form of locking means serves to resist this pressure and holds the core head firmly down against the molds, resulting in a high degree of uniformity in the baked cups.

The batter supply mechanism 40 comprises a rolling tray 120 suspended by straps 121 from rails and having rolling engagement thereon by means of wheels 122 having their bearings in straps 121. By this construction the batter supply tray may be moved along the rails to register with successive units and when all have been supplied the tray may be returned to a position at the left of the machine out of registration with any of them.

The tray 120 has a sheet metal bottom 124 and upstanding walls 125 (Figs. 6, 7, and 8). Spaced bars 126 extend lengthwise of the tray and partitions 127 are provided to fill the spaces between the bars. These partitions have their tops in the form of an inverted V, as clearly shown in Fig. 8, permitting the batter to flow and fill the spaces between the partitions. Discharge openings 128 are formed in the bars and tray bottom, the openings being normally closed by a frame comprising a multiplicity of closure slides 129, one for each opening, spaced apart and connected in rows to slide bars 130, which in turn are attached to a cross bar 131. The port closure frame is operated by a handle 132 journalled

at 133 on a lug 134 projecting from a cross bar 135 which is a part of a subframe connected to the main frame of the tray.

The handle 132 at its lower end has a pin and slot connection with the cross bar 131 of the part closure frame. A spring 136 pulls the handle in a direction to close the discharge opening.

After the mold carrier has been withdrawn from the ovens, the contents of the molds discharged, and the molds re-closed as herein previously described, the batter supply tray is moved along the rails into exact registration with the mold carrier. The operator then moves the handle 132 opening each of the ports 128 simultaneously, letting drop a quantity of batter in each of the mold cavities. As the operator releases the handle 132 the spring 136 returns the slide frame to close the ports. An equal quantity of batter is dropped into each cavity. An adjustable stop 140 is provided for arresting the movement of the handle 132. The operator releases the handles as soon as this stop is reached so that by varying the position of the stop the opening time of the ports may be varied. This provides for gauging the amount of batter delivered to the molds.

To more accurately determine the amount of batter delivered, the form of delivery tray shown in Figs. 11 and 12 may be used. In this form the tray bottom is above the valves as indicated at 150 and rotary plug valves 151 are arranged below. The valve casings 151 have upper and lower ports 152 and 153 respectively. The valve plug has a port 154 adapted to be moved into and out of registration with the inlet port 152. The plug has an outlet port 155 adapted to be moved into and out of registration with the delivery port 153. Lengthwise of the valve plug, which is hollow, there are partitions 156 forming chambers, so that when the tray is filled with batter and the valve inlet ports registered with openings 157 in the tray bottom, a quantity of batter will be received in each chamber. Each valve plug has at one end a lever 158 connected to a bar 159. The bar is operated by a handle 160 between adjustable limiting stops one of which is shown at 161. If desired a spring may be used for effecting the return movement.

The split female molds are shown as having top plates 170 providing lips 171 with recesses 172 for the batter overflow.

The advantages of these plates are fully set forth in my copending application Ser. No. 77,910, filed December 28th, 1925, for improvements in automatic machines for making cup pastry. These plates have one special advantage in the present machine not apparent in the automatic machine. The lips 171 form the opening which receives the fingers 73 of the extracting rake 70. In the op-

eration of separating the split molds by the use of the rake the baked product is protected from injury by the lips of the plates.

Having described the invention what is claimed as new is:

1. In a machine for making edible containers in combination, a main frame, a plurality of baking units therein, each baking unit comprising a heater, a core head having a multiplicity of cores located at the heater, and a sub-frame, provided with a multiplicity of molds, slideable to and from the heater, and a batter supply device successively moveable to each of said plurality of baking units to register with the mold frames when the latter have been moved from the heater. 70

2. In a machine for making edible containers in combination, a main frame, a plurality of baking units therein, each baking unit comprising a heater, a core head having a multiplicity of cores located at the heater, and a sub-frame, provided with a multiplicity of molds, slideable to and from the heater, a batter supply device successively moveable to each of said plurality of baking units to register with the mold frames when the latter have been moved from the heater, and a discharge chute to which the mold frames are moved from the heaters. 80

3. In a machine for making edible containers, in combination, a main frame, a plurality of baking units therein, each baking unit comprising a heater, a core head having a multiplicity of cores located at the heater, and a sub-frame, provided with a multiplicity of molds, moveable to and from the heater, a handle and connected actuating means for moving the sub-frame to and from the heater, a handle and connected actuating means for moving the core head to and from the sub-frame when the latter is at the heater. 95

4. In a machine for making edible containers, in combination, a main frame, a plurality of baking units arranged in a row therein, a single batter delivery device arranged for movement across the row to register as needed with any of the baking units, each unit comprising a plurality of separable mold halves in a slideable frame, heating means fixed to the main frame and a moveable core head having a multiplicity of cores located opposite the heating means. 100

5. In a machine for making edible containers, in combination, a main frame, a plurality of baking units arranged in a row therein, each unit comprising heating means at the rear of the machine, a mold carrier mounted on the frame for movement from front to rear of the machine, a core carrier at the heating means actuating means for moving the mold carrier to and from the heater, actuating means for moving the core carrier into and out of the molds, and a single batter delivery device arranged for movement across the row 110

125

130

to register as needed with any of the baking devices.

6. A machine for making edible containers comprising a plurality of baking units arranged in a row, each baking unit comprising a fixed heating device, a multiplicity of cores located at the heating devices respectively, and a multiplicity of female molds slidably arranged on the machine so that they may be introduced between the heating devices and the cores for the baking operation, and so that they may be withdrawn from the heating devices for discharging and refilling.

7. In a machine for making edible containers, a plurality of baking units arranged in a row, a rectilinear frame for each unit, each frame having a plurality of split female molds slidably mounted to open and close in said frame, a device for supplying to the split female molds when closed the material to be baked, said device being movable along the row into successive positions of registration with the different mold frames.

8. In a machine for making edible containers, a plurality of baking units arranged in a row, a rectilinearly slidable frame for each unit, each slidable frame having a plurality of split female molds slidably mounted to open and close in said frame, a device for supplying to the split female molds when closed the material to be baked, said device being movable transversely of the units and along the row into successive positions of registration with the different mold frames.

35 9. In a machine for making edible containers, in combination, a main frame, a baking unit therein comprising a heater, a core head having a multiplicity of cores located at the heater, and a sub-frame, provided with a multiplicity of molds, movable to and from the heater, a handle and connected actuating means for moving the mold frame to and from the heater, a handle and connected actuating means for moving the core head to and from the mold frame when the latter is at the heater.

50 10. In a machine for making edible containers, in combination, a main frame, a baking unit therein, a batter delivery device, the baking unit comprising a plurality of separable female mold halves in a slidable sub-frame, heating means fixed in position relatively to the main frame, and a movable core head, having a multiplicity of cores at the heating means.

55 11. In a machine for making edible containers, in combination, a frame structure comprising rails, a carriage adapted to roll on said rails, a plurality of divided female molds relatively slidably on said carriage and separable therein, an actuating device for the carriage and means adapted to close the separated molds.

60 12. A machine for making edible containers, comprising a baking unit having a fixed

heating device, a multiplicity of cores located at the heating device, and a multiplicity of female molds slidably arranged on the machine so that they may be introduced between the heating device and the cores for the baking operation, and so that they may be withdrawn from the heating devices for discharging and refilling.

70 13. In a machine of the character described, in combination, a frame, a heater and cores arranged at the rear of the frame at a baking location, a plurality of divided female molds movable on said frame to the baking location and movable therefrom to a discharge and batter supply location at the front of the machine, and a batter supply device arranged to be cooperative with the female molds when the latter are closed at the batter supply location.

75 14. In a machine of the character described, in combination, a baking means comprising a multiplicity of cores and heating agencies therefor, and a fixed heating device arranged below and spaced from said cores, a mold carrier having a plurality of split molds and being adapted for movement into and out of the space between said cores and the fixed heating device, means for discharging the split molds of their baked contents comprising a finger adapted to be entered into the mold cavities and given a raking action whereby the molds are opened and the baked product dislodged.

80 15. In a machine of the character described, in combination, heating means, cores, a mold carrier movable toward and from the heating means, a plurality of split female molds slidably arranged in said carrier and adapted to be separated therein for purposes of discharge, a rake for separating said molds, and a device for closing and locking the molds.

JAMES DENARO.
